MACKNEELE COX, OF STOLLINGS, WEST VIRGINIA, ASSIGNEE OF ONE-HALF TO
H. M. MCKEE, OF PEACH CREEK, WEST VIRGINIA.

CABLE HOOK.

Application filed January 21, 1925. Serial No. 3,882.

This invention relates to a cable hook designed primarily for use in connection with the motor of mine cars or mining machines with which it is customary to employ a reel, but it is understood that a cable hook, in accordance with this invention can be employed for any purposes wherein it is found applicable, and the invention has for its object to provide, in a manner as hereinafter set forth, a cable hook which is effectively insulated for protecting the operator, which overcomes the application of sudden jerks to the reel when starting the car or machine thereby preventing injury to the reel, prevents sudden tension on the cable which otherwise would inflict injury to or perhaps breakage thereof, and for preventing blow outs as the hook is of the yieldable type.

Further objects of the invention are to provide, in a manner as hereinafter set forth, a cable hook which is simple in its construction, strong, durable, compact, thoroughly efficient and convenient in its use, and comparatively inexpensive to manufacture.

With the foregoing and other objects in view, the invention consists of the novel construction, combination and arrangement of parts as hereinafter set forth and illustrated in the accompanying drawings, wherein is shown an embodiment of the invention, but it is to be understood that changes in the details of construction can be had which fall within the scope of the claims hereunto appended.

In the drawings wherein like reference characters denote corresponding parts throughout the several views:

Figure 1 is an elevation of a cable hook in accordance with this invention.

Figure 2 is a longitudinal sectional view thereof.

Figure 3 is a section on line 3—3, Figure 2.

Figure 4 is a fragmentary view, in longitudinal section, taken at right angles to Figure 2.

Referring to the drawings in detail 1 generally denotes a substantially elongated outer casing of insulation material throughout, having a closed bottom and an open top. The casing 1 is formed with an elongated tubular portion 2 for the major portion of its length and a hollow flattened lower terminal portion 3 of a width greater than the diameter of the

portion 2. The lower terminal portion 3 of the casing 1 is formed with a pair of oppositely extending converging portions 4 which provide the inner face of the casing between the portions 2, 3, with a pair of oppositely extending bevelled shoulders 5, which overhang with respect to the portion 2 and provides a retaining means for an inner casing formed of conducting material and to be presently referred to. The portion 3 is formed with a pair of aligning openings 6 with the walls thereof oppositely flared with respect to each other, as at 7, 7'.

The inner casing, which is referred to generally by the reference character 8, comprises a tubular portion 9, a flat lower terminal portion 10 and an intermediate converging portion 11. The tubular portion 9 is of greater length than the tubular portion 2 and projects above the top of the latter. The portion 10 is of greater width than the diameter of the portion 9, and snugly engages the inner face of the portion 3. The portion 11 snugly engages the shoulders 5, and as these latter overhang said portion 11, they act as a retaining means for maintaining the casings 1 and 8 coupled together to prevent the separation of one from the other. The portion 10 is formed with an opening 12 which registers with the openings 6, and otherwise than that as stated the portion 10 is solid. The upper part of the portion 11 is formed with a concavity 13 having the wall thereof form a continuation of the inner face of the portion 9, and the latter in connection with the concavity 13 provides a chamber 14 in which operates the inner portion of the shank of a hook to be presently referred to. The bottom of the chamber 14 is provided by the portion 11 and the top of said chamber opens at the upper end of the portion 9. That part of the portion 9 which projects above the casing 1, is indicated at 15 and is provided with peripheral threads 16 with which engages an internally threaded combined closure and retaining cap 17, formed of insulation material, and is provided at its lower end with a lateral annular flange 18; its periphery is provided with lengthwise extending diametrically opposed gripping ribs 19, only one of which is shown, and its top is provided with an axial opening 20. The cap 17 when mounted in position closes the upper end of the portion 9, seats on the top edge of the casing,

acts as a guide for the hook element and also as a retaining means for the spring controlling means for the hook element.

Extending through the opening 20, is the hook element which comprises a substantial elongated shank 21, provided at its outer end with a hook 22, at its inner end with a disk 23 and intermediate its ends with a slidable collar 24. Mounted on the shank and supported by the disk 23 is a collar 25 of conducting material having a snug, but sliding fit with the inner surface of the tube 9.

That portion of the shank 21, within the chamber 14, carries a pair of controlling springs 26, 26', the latter is interposed between the collar 24 and the top of the cap 17, and the former between the collars 25 and 24. The springs 26, 26', collars 24, 25 and cap 17 provide a resilient or yielding coupling or cushion, between the hook element and the cable 27 which is attached to the flattened portions of the casings 1 and 8, when the hook element is connected to the conductor 28, and it is this resilient or yielding coupling or cushion which overcomes sudden jars on the reel employed in connection with the mine car or mining machine.

The cable 27 is extended through the aligning openings 6 and 12 and secured together, as at 29, to provide a loop connection 30 with the casings 1 and 8.

The hook 22 is so formed as to enable it to be quickly connected to and removed from the conductor 28, when desired and for such purpose the back of the hook, as well as the bill thereof, is disposed at an inclination, as indicated at 31, 32, respectively.

The casing 1 and cap 17, being formed of insulation material, act to effectively protect the operator, when gripping the casing 1 to connect to the cable 28. The length of the casing 1 is to be materially greater than the width of the hand of the operator. The cable 27 electrically connects with the portion 10 of the casing 8, but if the cable 27 is of the insulated type a portion of its length is bared so that contact can be had with the portion 10, and although the preferred embodiment of the invention is as described and shown, yet it is to be understood that changes in the details of construction can be had which fall within the scope of the invention as claimed.

What I claim is:—

1. A hook for the purpose set forth comprising an outer casing of insulation, an inner casing of conducting material extended from the upper end of the outer casing, said casings having inherent snugly engaging means at their lower portions to prevent the lengthwise separation thereof, a hook element extending into said inner casing and electrically contacting therewith and spaced from said inherent means, cushioning means surrounding and supported by said element, non-conducting means engaging with the extended part

of said inner casing, abutting against the outer casing and surrounding said element for confining said cushioning means, under a state of compression, within said inner casing, and the said inherent means of said casings having registering openings for coupling a cable therewith. 70

2. A hook for the purpose set forth comprising an outer casing of insulation open at its upper end and closed at its lower end, an inner casing of conducting material closed at its lower end and open at its upper end and extended from the upper end of the outer casing, said inner casing having its lower end seated upon the inner face of the lower end of the outer casing, said casings having the lower ends thereof provided with registering openings for coupling a cable therewith, said casings having their lower portions compressed and extended to provide inherent snugly engaging means to prevent the lengthwise separation of one casing relative to the other, a hook element extending into said inner casing and carrying means for electrically connecting it with said inner casing, the inner end of said hook element being spaced from the lower end of said inner casing, said hook element extended from the upper end of the inner casing, a pair of spaced cushioning elements surrounding and supported by said hook element, non-conducting means engaging with the extended part of said inner casing, abutting against the upper end of the outer casing and surrounding said hook element for confining said cushioning elements under a state of compression within said inner casing. 90

3. A hook for the purpose set forth comprising an outer casing of insulation closed at its lower end and open at its upper end, an inner casing of conducting material closed at its lower end and open at its upper end and projecting from the upper end of the outer casing, said casings at their lower ends being laterally extended to provide inherent snugly engaging means to prevent the lengthwise separation of one casing relative to the other, a hook element extending into said inner casing and provided with a disc at its lower end, a contact member supported on said disc and contacting with said inner casing and further spaced from the lower end of the latter, a slidable collar on said hook element, a non-conducting means engaging with the extended part of the inner casing, abutting the upper end of the outer casing and provided with an opening for the passage of said hook element, a controlling spring surrounding said hook element and interposed between said collar and said contact member, and a controlling spring surrounding said hook element and interposed between said collar and said cap. 110 115 120 125

In testimony whereof, I affix my signature hereto.

MACKNEELE COX.
